CLAIM

I claim the ornamental design for a card reader, as shown and described.

DESCRIPTION

FIG. 1 is a perspective view of a first embodiment of a card reader, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and

FIG. 7 is a right side elevational view thereof.

FIG. 8 is a perspective view of a second embodiment of the card reader; and,

FIG. 9 is a front elevational view thereof.

The rear, top, bottom, left side, and right side of the second embodiment are identical to those of the first embodiment, and therefore not shown.

Broken lines are for illustrating unclaimed portions of the card reader; the broken lines form no part of the claimed design.
